US00D700351S

(12) United States Design Patent
Kojima

(10) Patent No.: US D700,351 S
(45) Date of Patent: * Feb. 25, 2014

(54) MASSAGE TOOL

(71) Applicant: Yukiko Kojima, Tokyo (JP)

(72) Inventor: Yukiko Kojima, Tokyo (JP)

(73) Assignee: ELC Management LLC, Melville, NY
(US)

() Term: 14 Years

(21) Appl. No.: 29/444,086

(22) Filed: Jan. 25, 2013

(51) LOC (10) Cl. 28-03

(52) U.S. Cl.

USPC D24/215
